UNITED STATES PATENT OFFICE.

BENJAMIN F. PALMER, OF TULSA, OKLAHOMA, ASSIGNOR TO PAUL ARBON, OF TULSA, OKLAHOMA.

OIL-WELL CONTROL-HEAD VALVE.

Application filed February 23, 1924. Serial No. 694,678.

This invention relates to oil well control head valves.

One object of the invention is to provide a control head valve which is adjustable to cut off communication between the well and atmosphere while leaving open the way for the flow of oil from the well to the storage tanks, and which is also adjustable to cut off communication between the well and tanks while allowing any oil in the drill tubing above to drain off into the tanks, which operations of the valve are permissible without interference from the drill cable extending therethrough.

Another object of the invention is to provide a valve embodying thrust bearings so constructed and arranged as to sustain the valve and keep it centered against all working pressures, operating to prevent freezing of the valve under high pressures and to reduce to a minimum liability of grinding contact between surfaces tending to produce sparks and to cause a conflagration.

Still another object of the invention is to provide means whereby, in case of an accidental fire, steam may be injected in a novel and most efficient means for a snuffing action to extinguish the fire.

Still another object of the invention is to provide a control head valve which is simple of construction, reliable and efficient in action, smooth and easy of adjustment, and so constructed as to admit of ready and convenient assemblage of its parts for use and their disassemblage for inspection, cleaning, repairs or other purposes.

The invention consists of the features of construction, combination and arrangement of parts, hereinafter fully described and claimed, reference being had to the accompanying drawing, in which:—

Figure 1 is a view in elevation looking toward one side of the control head.

Figure 2 is a vertical longitudinal section through the same.

Figure 3 is a vertical transverse section on line 3—3 of Figure 1, showing the valve member in one of its positions.

Figure 4 is a similar view showing the valve member in another position.

Figure 5 is a horizontal section on line 5—5 of Figure 3.

Figure 6 is a detail view of the valve member per se.

The control head valve embodying my

valve comprises a casing 1 having a central bore 2 of circular contour. Communicating with the top and bottom of this bore are aligned vertical passages 3 and 4, and communicating with opposite sides of the bore are aligned horizontal passages 5 and 6. The passage 3 is counterbored at its upper end to receive the overhead drill tube or oil-saver of standard make and provided with fastening devices 7 for engagement therewith, while the passage 4 is counterbored and internally threaded for engagement with the upper end of the well tubing 8. At one end the casing is formed with a chamber or recess 9 communicating at its inner side with the bore 2 and closed at its outer side by a fixed wall or head 10, and at its diametrically opposite side the casing is provided with an opening 11 communicating at its inner side with the bore 2 and closed at its outer side by a detachable head 12 secured in position by stud bolts 13 and nuts 14; a gasket 15 being disposed between the face of such end of the casing and the head 12 to form a tight joint and the head 12 being provided with an inwardly extending flange 16 snugly fitting within the opening 11 so as to center the head in position and supplement the joint closing action of the gasket 15.

Fitted within the casing is a rotary control valve 17, said valve comprising a pair of circular end disks or heads 18 and 19 and a web 20 connecting said disks or heads at one side. This web 20 is approximately of quadrantal form, that is, extends substantially around one quarter of the circumference of the valve, the valve being otherwise open between the heads or disks 18 and 19. The said heads or disks 18 and 19 are formed to respectively fit snugly within the chamber 9 and opening 11 and to turn or rotate therein, and are provided with annular peripheral grooves 21 receiving suitable packing material 22 to close the joints between the peripheries of the disks and the walls of the said chamber and opening against the escape of oil or gases from the interior of the control head.

The disks 18 and 19 are provided with flat inner faces merging into the curved portions of the inner face of the web 20, so that the inner surfaces of the disks and the web will accurately align with the bore 2 and walls of the passages 3, 4, 5 and 6 when the valve is

in position for connecting any one or more of such passages with the bore, so as to secure a flow of the oil and gases without agitation or interference. The valve 17 is adjustable to the position shown in Figure 3 for cutting off communication between the well tubing 8 and the passage 6, and to the particular storage tank or reservoir to which said passage leads. The valve is also adjustable to 5 the diametrically opposite position from that shown in Figure 3 to close communication between the tubing 8 and passage 5 and the storage tank or reservoir to which said passage leads. The valve is further adjustable to 10 to the position shown in Figure 4 to cut off communication between the well tubing 8 and the atmosphere. The valve is still further adjustable to a position diametrically opposite that shown in Figure 4, so as to cut off the flow of oil from the tubing 8 to the control head and to both passages 5 and 6, the last-named position resulting in the closure of the well against any discharge of oil. The drill line or cable 23 extends as 15 usual downward through the control head and the valve 17 and the valve web 20 is provided in its diametrically opposite edges with notches 24 and 25 to receive and accommodate the cable when the valve is adjusted to one or the other of the last-named positions, said notches extending inwardly a sufficient distance from the valve edges to permit the web to have the proper lapping engagements for a closing action against the 20 flow of oil, this construction allowing the valve to be closed to cut off communication between the well and the atmosphere or to wholly cut off the flow of oil from the well without interference from the drill cable. 25 As shown, the walls of the casing bore are provided, at their points of intersection with the passages, with bearing surfaces 20^a, and the outer surface of the web is provided in the region of its end edges with rounded 30 bearing faces 20^b to engage said bearing surfaces 20^a, the said outer face of the web being otherwise substantially flat, as shown at 20°, between said bearing faces 20^b and lying within the adjacent portion of the periphery of the valve. Grooves 26 extend across the said bearing faces 20^b of the web between the disks 18 and 19, and receive packing strips 27, of copper, bronze or other suitable material, for effecting a fluid tight 35 engagement between the valve and its seat faces without wear upon the valve body itself. 40 The valve is provided at one end with a spindle or shaft 28 which is journaled in and extends outwardly through an opening 29 in the head 12 and through a suitable stuffing box 30, provided for an obvious purpose, the outer end of said shaft or spindle terminating in an angular portion 31 for the reception of a handle, wrench or other valve op-

erating device. Formed upon each end of the valve is a journal 32, which journals project respectively into annular bearing chambers formed by inwardly projecting annular bearing ribs 33 on the wall or head 10 and the head 12, and the opposed faces of the coacting journals and bearing ribs are shaped to form raceways for anti-friction bearing balls 34, thus providing an anti-friction support and bearing surface for each end of the valve. These bearing surfaces, including the balls, may be fairly large or of heavy duty type allowing the valve to have free and easy motion for adjustments under all conditions. This construction of the bearing surfaces provides an arrangement of the bearings which will sustain the valve securely against all internal pressures, preventing the valve from freezing under high pressure and also maintaining the valve in a fixed or centered position so as to avoid any undue friction and grinding of metal against metal tending to produce sparks liable to cause a conflagration. By this mode of mounting the valve these advantages are secured in a simple manner and binding of the valve prevented, so that no matter how high the internal pressure within the valve may be adjusted for any of the controlling actions described. The described construction and mode of mounting the valve also admits of the easy and convenient assemblage of the parts and their disassembly for inspection, cleaning, repairs and all other purposes whenever required. By relieving the valve of all excess wear and tear, its life period is also considerably prolonged and shut-downs or accidents ordinarily caused by binding valves effectually prevented. The described form of the valve, composed of the end disks and web, is furthermore of advantage in providing a passage free from obstructions liable to cause agitation or interference with the free flow of the oil and gases in the intended direction.

The disk 18 is provided with an axial opening 35 extending through its inner face and which communicates with a socket or recess 36 of relatively larger diameter formed in its outer face, and which socket or recess in turn is arranged in alignment with an opening 37 formed in the head or wall 10. Fitted in said socket or recess 36 is a bushing nozzle 38 provided with jet passages 39 extending in parallel relation transversely thereof. These passages are V-shaped on their inlet side and terminate on their outlet side in restricted delivery portions in the form of slits projecting lengthwise at right angles to the plane of the inner wall of the web 20, said slits being inclined in opposite directions parallel to the plane of the wall and toward diametrically opposite sides of the valve. The opening 37 receives the delivery end of a pipe 130

40 containing a check valve 41 and leading from a suitable source of high pressure steam supply. At any suitable point in this pipe a valve for governing the supply of steam to the bushing nozzle may be provided. This construction provides a steam snuffer of simple and highly efficient type for extinguishing flames in the event that through accident or other cause, the oil or gas within the 10 well casing or control head should catch afire. Under such conditions, the valve may be shifted to either of its upper or lower closed positions and jets of steam forced at upward and downward angles into the control head thus blanketing the flames and causing their rapid extinguishment.

Having thus fully described my invention, I claim:

1. In a control head valve for well drilling apparatus, a casing having upper and lower vertically aligned passages and horizontal transversely aligned passages in opposite sides thereof, said passages intersecting the bore of said casing, one end of said 20 casing having an opening extending outwardly from said bore and the other end of said casing having a recess extending outwardly from the bore and provided with an integral closing wall, a detachable closure 25 for said opening, and a rotary valve mounted in said casing, said valve comprising circular end disks fitted to turn respectively within said opening and recess and snugly engaging the peripheral walls thereof and 30 a segmental web connecting said disks, the walls of the casing bore being provided with bearing surfaces at their points of intersection with the passages, and said web having line receiving recesses in its transverse edges 35 and having its outer surface provided adjacent to its edges with rounded bearing faces to engage said bearing surfaces of the walls of the bore, the outer face of said web being otherwise flat between said bearing surfaces and lying within the adjacent 40 portion of the periphery of the valve.

2. In a control head valve for well drilling apparatus, the combination of a casing having two pairs of vertically and laterally aligned passages, and having a wall provided with an opening therein, a steam supply conductor fitted within said opening, a rotary valve comprising spaced end disks and a segmental portion fitted within said casing, one of said disks being provided with an opening registering with said steam supply pipe and communicating with the space between the disks, and a bushing nozzle fitted in said opening in the disk and having jet passages with delivery portions inclined toward diametrically opposite sides of the valve.

3. In a control head valve for well drilling apparatus, a casing having a pair of vertically aligned passages and a pair of laterally aligned passages, and having a wall provided with an opening therein, a steam supply conductor fitted within said opening, and a rotary valve comprising spaced end disks and a segmental portion connecting said disks, one of said disks being provided with an opening registering with said steam supply pipe and communicating with the space between the disks.

4. In a combined snuffer and control head 75 for oil and gas wells, a body member adapted to be connected to the upper end of a well casing and having a central passageway and lateral openings communicating with said passageway, a valve member controlling certain of said lateral openings and said passageway, and ports connecting other of said openings with the passageway, said ports and valve being so arranged as to permit the passageway to be closed by the 80 valve and the steam to be fed into the passageway on the inlet side of the closed valve, the central passageway being unobstructed 85 below said valve.

In testimony whereof I affix my signature.

BENJAMIN F. PALMER.
